UNITED STATES PATENT OFFICE.

ALBERT LEE WARREN, OF RAY, ARIZONA.

AUGER.

1,293,265.

Specification of Letters Patent.

Patented Feb. 4, 1919.

Application filed January 3, 1917. Serial No. 140,383.

To all whom it may concern:

Be it known that I, ALBERT LEE WARREN, citizen of the United States, residing at Ray, in the county of Pinal and State of Arizona, 5 have invented new and useful Improvements in Augers, of which the following is a specification.

This invention relates to augers designed for cutting mortises, and its object is to provide 10 a simple and efficient device of this kind composed of a pair of rotary mortising cutters associated with an ordinary auger, the structure being such that the mortising cutters can be readily applied to the auger.

15 In order that the invention may be better understood, reference is had to the accompanying drawing forming a part of this specification, and in said drawing—

Figure 1 is an elevation of the invention, 20 partly in section;

Fig. 2 is a section on the line 2—2 of Fig. 3, and

Fig. 3 is an enlarged horizontal section on the line 3—3 of Fig. 1.

25 Referring specifically to the drawing, the invention is shown applied to an auger of conventional design having a stem 5 provided with a spiral thread 6 wrapped around the same, with a screw point 7 at the outer 30 end of the stem, and cutting lips 8 adjacent to the said point.

The mortising cutters are located just back of the cutting lips 8, and two of such cutters are provided, they being mounted on opposite 35 sides of the stem 5. In order to accommodate the cutters the thread 6 stops short of the cutting lips 8 leaving the stem 5 blank and devoid of a thread here.

Each mortising cutter is in the form of a 40 wheel 9 having outstanding blades 10 on its periphery. The cutter is rotatably mounted on a support carried by the stem 5. This support is in the form of a split sleeve 11 loosely encircling the stem 5 and having diametrically opposite outstanding shaft extensions 12 on which the cutting wheels are 45 mounted to turn freely thereon. The two sections of the sleeve are clamped together by screws 13 passing through said sections 50 and drawing the same together. Each sleeve

section has lateral extensions, and when the sections are assembled said extensions come together and form shafts on which the cutter wheels are rotatably mounted. The cutter wheels are held on the shafts by any suitable 55 means such as cotter pins 14 and washers 15.

The inner face or side of each cutter wheel 9 has bevel gear teeth 16, and these teeth of both wheels are in mesh with a bevel gear 17 fast on the stem 5, said bevel gear 17 being 60 mounted on that part of the stem 5 which is devoid of threads and which is located between the cutter wheels.

It will be seen from the foregoing that when the auger is turned and advanced 65 through the work, the cutter wheels 9 are carried along with the auger and at the same time they are rotated about their axles to cut a mortise.

The outer faces of the cutter wheels have 70 recesses 18 in which the fastening devices 14 and 15 are housed, leaving the said face smooth and devoid of projecting parts. The auger stem 5 turns in the sleeve 11, in view of which it will be seen that the cutting 75 wheels 9 do not revolve with the stem but rotate about their own axes only. In order to prevent the sleeve from slipping up or down on the stem, the latter has an annular groove 19 in which the sleeve seats. 80

I claim:

The combination with an auger comprising a stem having a spiral thread wrapped around the same, and provided with a screw point and cutting lips back of the screw 85 point, the thread terminating short of the cutting lips to leave a portion of the stem back of said cutting lips blank, said blank portion having an annular groove, a split sleeve loosely mounted in the groove and 90 having outstanding shaft extensions, means for connecting the sleeve sections, rotary mortising cutters mounted on the shaft extensions and having bevel gear teeth on their inner faces, and a bevel gear on the stem 95 and in mesh with the gear teeth of the cutters.

In testimony whereof I affix my signature.

ALBERT LEE WARREN.
